UNITED STATES PATENT OFFICE

FREDERICK A. GERCICH, OF OAKLAND, CALIFORNIA, ASSIGNOR TO HAMMER-BRAY COMPANY, OF OAKLAND, CALIFORNIA, A CORPORATION OF CALIFORNIA

GAS STOVE

Application filed November 17, 1927. Serial No. 233,864.

The invention relates generally to a closed top gas stove having means provided in the top-gas-burner chamber thereof for controlling the supply of secondary air to the burners in said chamber, and more particularly to the structure of said means and the support of said burner in the chamber. This application is related to my original application Serial No. 186,610, which was filed in the Patent Office on April 26, 1927, the present application relating more particularly to the embodiment illustrated in Figure 4 of said original application.

An object of the invention is to provide a gas stove structure in which the means for controlling the secondary air supply to the burners provides the support for the burners.

Another object of the invention is to provide a structure whereby the independent and ready removal and installation of the burners is provided for.

The invention possesses other objects and features of advantage, some of which, with the foregoing, will be set forth in the following description of the preferred form of the invention which is illustrated in the drawings accompanying and forming part of the specification. It is to be understood, however, that variations in the showing made by the said drawings and description may be adopted within the scope of the invention as set forth in the claims.

Referring to said drawings,

Figure 1 is a fragmentary plan view of a stove embodying the structure of my invention and having the cooking-top lid-plate thereof removed.

Figure 2 is a sectional view taken on the line 2-2 in Figure 1.

Figure 3 is an enlarged fragmentary sectional view taken on the line 3-3 in Figure 1.

Figure 4 is a view similar to Figure 3 showing a different embodiment of the invention, the cooking-top lid-plate being omitted.

As herewith particularly disclosed, the means of my invention is incorporated with a gas stove 6 having a cooking top 7 beneath which is defined a burner compartment 8 in which are suitably mounted front and back

burners 9 and 11 respectively. The compartment 8, it will be noted, is defined between side walls 12, a front wall 13, a back wall 14, a bottom wall 15 and the cooking top 7. Fresh air is arranged to be admitted to said compartment to escape from the compartment at a point adjacent the cooking top—as here shown, the side and bottom walls of the compartment are imperforate, while the front and back walls are perforated to provide respectively for the ingress and egress of fresh air and vitiated air. The cooking top 7 is of a usual structure and comprises a removable lid-carrying section 16 mounted on a rim section 17 forming a fixed part of the stove, it being noted that the section 16 overlies the various burners of the compartment 8. Preferably, and as here shown, the burners 9 and 11 are of a type having their jets projected upwardly from the top surfaces 18 thereof.

Mounted in the compartment 8 is a member 19, such member having a bottom plate portion 21 disposed slightly above the plane of the burner surfaces 18, and provided with circular openings 20 over the burners to allow the protrusion therethrough of the flame jets of the burners—in practice, it has been found that the positioning of the plate 21 about one-eighth of an inch above the burner surfaces 18 is best. As here shown, the plate 19 is of substantially the same size and shape as the top section 16 and is provided at the edges thereof which are respectively opposite the side walls 12 and front wall 13 with wall portions 22 extending upwardly of the plate portion 21. Preferably, the walls 22 are coterminous and extend to and against the top rim section 17 and are secured thereto in any suitable manner whereby they serve to entirely support the member 19 in the compartment with plate 21 in its operative position. The plate 21 preferably extends to and against the perforated back wall 14 of the compartment, it being noted that when, as here shown, the vent opening 23 of such wall extends below the level of the plate 21, a back edge portion 24 of the latter is deflected downwardly to register with the bottom edge of the opening. In this manner, the member 19 cooperates with the cooking top to define there-

with a heating chamber 25 having its only inlets for air at and around the burners 9 and 11 and its only exit for air at the vent opening 23, whereby air may enter the chamber 25 only through the plate perforations at the burners and will be directed upwardly through the flames at the burners and thus be fully available as a secondary air supply therefor, it being noted that the remaining portion 26 of the compartment 8 thus functions purely as an air supply chamber.

As herewith particularly disclosed, the support of the member 19 from the cooking top rim section 17 is effected by providing depressed portions 27 in a seat 28 provided around the perforation of section 17 for the reception of the removable top section 16, in which seat portions lateral extensions 29 provided at the top of the plate portions 21 of the member 19 are arranged to be disposed. In this manner, the removable support of the member 19 from the rim section 17 is provided independently of and does not interfere with the mounting of the top section 16 thereon.

Preferably, and as here shown, a conduit member 31 is mounted in each of the openings 20 of plate 21, and is so formed that air passing through the passage provided thereby will be guided into the flame space of the jets above the different burners. In the present embodiment of the invention in which the burners shown are provided with arms 32 radiating from a common center and having rows of jets 33 extending longitudinally therealong, the conduit passage 34 is of the general outline of the burner and is formed with portions 36 overlying the different burner arms 32. Preferably, and as here shown, the passage portions 36 are no wider at their inlet ends than the adjacent portions of the arms which they overlie, and may, to advantage, be even narrower. In this manner, the air passing upwardly around the burner arms and into the passage is directed transversely against the jet flames, whereby all of the oxygen of the air passing through the conduit is made available at the burner flames to insure complete combustion thereat. Preferably, and as here shown, the exit end of each passage 34 is disposed substantially at the plane of the tips of the combustion cones of the burner flames when such are of full size, so that vitiated air from one burner may not interfere with the combustion at another burner, it being noted that the flame space of the burner is thus defined in the conduit passage 34 and immediately below it.

As herewith particularly disclosed, each conduit member 31 comprises a base portion 37 perforated to provide the lower end of the passage 34 and having a continuous wall 38 of substantially uniform thickness extending upwardly from around its perforation 65 to define the passage 34, it being noted that

the folds of said walls define arm portions 39 thereof which provide the passage portions 36 overlying the different burner arms. In this manner, the conduit members are arranged to be of a minimum weight. The peripheries of the bases 37 are arranged for disposal in depressed annular seats 41 provided in the edges of the perforations 20 whereby the members 31 are held against shifting over the plate surface. To insure a correct positioning of the conduit members in the seats 41, extensions 42 are provided on the plate 21 at each of the seats 41, such extensions being directed radially inwardly for engagement with notches provided in the edges of the conduit base portions 37.

The burners, it will be noted, are also arranged to be supported from the plate 21, and, as particularly disclosed in Figures 1, 2 and 3, are provided with one or more webs 43 connecting adjacent arms 32 thereof whereby they may be secured to the members 31 as by bolts 44, spacing bosses 45 being provided on the members 31 whereby the burners and members may be properly spaced apart. If desired, the burners may be supported directly from the partitioning member, as is disclosed in the embodiment of Figure 4. In the latter embodiment, lugs 46 are provided on the burners 47, which lugs are arranged to be disposed in depressed portions 48 of the seats 49 provided in plate 21' for the reception of the bases 51 of the conduit members 31'. To prevent a relative rotative displacement of the members 31' with respect to the burners, the former are preferably provided with depending lugs 52 which are arranged to engage between adjacent burner arms 32' when the members are properly disposed with respect to the burners. In this manner, separate supporting means for the burners are rendered unnecessary.

In the present embodiment of the invention, the partitioning member is arranged to support a lighter 54 of the type whereby tongues of flame may be simultaneously directed therefrom over the various burners. Accordingly, and as particularly shown in the embodiment of Figures 1 to 3 inclusive, the member 19 is perforated as at 54' to receive the lighter 54 in position to discharge toward the various burners. Owing to the fact that the flame jets are above the plane of the plate 21, however, it is obviously desirable to provide special conduits leading from the lighter toward the burners and discharging through the conduit members 31 at the appropriate level. As here shown, the necessary conduits are provided directly in the plate 21 by forming the plate with generally semi-cylindrical grooves 55 extending upwardly of the lower plane of the plate 21 and opening downwardly, such grooves terminating at the conduit member perforation 130

and opposite conduit arms 39 which are appropriately perforated to complete the provision of open passages from the lighter to the burners. In this manner, open passages to the chamber 25 from the chamber 26 are avoided, as well as the provision of separate conduit parts for the lighter installation.

It will now be noted that the mountings provided for the conduits and burners are arranged to permit the movement of the burners to and from their operative positions through the perforations 20. But when, as is desirable and usual, the chamber 26 is relatively shallow, the relatively long lead pipes 51 of the rear burners which form integral parts of the burner structures would serve to prevent the insertion or removal of the burner while the member 21 is in its place. And, furthermore, an adjacent oven wall 56 or the splasher back 57 of the stove would still further hinder the insertion or removal of a rear burner. Means are accordingly provided for facilitating the removal or insertion of a rear burner through a perforation 20, and as here shown, such means comprises forming the member 19 with front and rear sections 64 and 66 respectively, whereby with the rear section 66 only in place, a rear burner may be removed or operatively positioned by moving it substantially vertically with respect to its operative position. Preferably, and as here shown, the member 19 is divided transversely thereof to define the sections 64 and 66, with the line of division lying generally forwardly of the rear burners and passing through each of the rear perforations 20.

Preferably, and as here shown, the abutting edge portions 67 and 68 of the sections 64 and 66 respectively are arranged to overlap each other in such manner that a certain degree of mutual support is provided by the sections when they are engaged. As here shown, the forward edge portion 69 of the rear section 66 which is defined between the pair of rear perforations 20 is arranged to be disposed in a seat 71 provided in the opposed edge portions 72 of the front section 64, the edge portions 73 of the section 64 which define parts of the perforations 20 are provided with portions 74 of the seat 41, and the remaining rear edge portions of the section 64 are arranged to be disposed in seats 76 provided in the opposed front edge portions 77 of the rear section 66.

It will, of course, now be obvious that the gap thus provided in the seat 41 when the section 64 is removed from its cooperative engagement with section 66 need only be wide enough to permit the lowering of the burner lead pipe 51 therethrough. Preferably, and as here shown, the seat portions 74 are provided in those portions of the section 64 which include the extremities of the lighter conduits 55, which conduit ends are here

shown disposed substantially midway of the front section edge portions 73 in which seat portions 74 are provided—in this manner, the lighting means is arranged to be carried entirely by the front section 64. And it will be further noted that the line of division between the sections is preferably carried as far forwardly as possible whereby the front section may be of the least possible weight.

Assembly of the structure described is arranged to be effected in a simple manner. With the lid plate 16 removed from the stove top, the section 66 is mounted in the rim section 17 by disposing its extensions 29 in the seat portions 27. Having secured conduit members 31 to the rear burners 11, these burners are then lowered into the compartment 8 to engage the conduit base portions 37 in the seats 41. The section 64 is then placed in position, it being noted that its rear edge must be engaged with cooperating front edge of section 66 and the conduits of the rear burners before the front of the section can be lowered to its set position. Insertion of the front burners and their conduits is now permitted, after which the lid plate 16 may be disposed in its opening. Removal of the burners would, of course, be effected by a reversal of the order of the before described steps. It will be noted that with the embodiment of Figure 4, the operative disposition of all of the burners in seated position is arranged to be effected independently of the conduits, the latter being placed in position after the burners and sections 64' and 66' are in place.

Owing to the concentration of heat at the vent opening 23 whereby the rear portion of plate 21 and the underlying portion of chamber 26 may become unduly heated, inlet openings 79 are also preferably provided in the rear wall 14 of the compartment 8 and below the plate 21, whereby air may enter the chamber 26 from the rear of the compartment, such air primarily serving to provide the rear burners with the necessary air for use therewith. In this manner, the circulation of air induced along the rear of plate 21 will provide a cooling of the plate and chamber and a corresponding preheating of such air.

I claim:

1. In a stove having a top-gas-burner compartment defined beneath a closed cooking top, a member dividing said compartment into upper and lower chambers and having a perforation therein; a seat at said perforation; and a burner disposed in said compartment adjacent said perforation and directly engaging said seat whereby it may be supported in position by and entirely below the plane of said member.

2. In a stove having a top-gas-burner compartment defined beneath a closed cooking top; a member dividing said compartment

into upper and lower chambers and having a perforation therein providing a seat at the edge thereof; a burner removably mounted in said seat and disposed entirely below the 5 plane of said member; and a conduit member removably mounted in said seat with its lower end substantially coplanar with said member and arranged to direct the air flowing upwardly through said perforation into the 10 flame space above said burner.

3. In a stove having a top-gas-burner compartment defined beneath a closed cooking top, a member disposed in said compartment to divide the same into upper and lower 15 chambers and having a perforation provided with a seat around the edges thereof, a burner disposed in said compartment and directly and removably supported in said seat, a conduit member removably mounted in said seat 20 independently of said burner and operative to direct the air flowing upwardly through said perforation into the combustion space directly above said burner, and a means integral with said conduit member for preventing only the angular displacement of 25 said last member with respect to said burner.

4. In a stove having a top-gas-burner compartment defined beneath a closed cooking top, a member dividing said compartment 30 into upper and lower chambers and having a perforation through a horizontally disposed portion thereof, a seat at and encircling said perforation and having depressed portions, a burner disposed in said compartment and 35 directly and removably supported in the depressed portions of said seat, and a conduit member removably mounted in said seat arranged to direct the air flowing upwardly through said perforation into the combustion 40 space above said burner, and provided with a means for preventing only the angular displacement of said conduit member with respect to said burner.

In testimony whereof, I have hereunto set 45 my hand at Oakland, California, this 5th day of November, 1927.

FREDERICK A. GERCICH.
